CABLE CUTTER HEAD

Leslie A. Repscher and William C. Stratman, Los Angeles, Calif., assignors to North American Aviation, Inc.

Application April 2, 1956, Serial No. 40,872

Term of patent 14 years

(Cl. D54—13)

FIG. 1

FIG. 2

FIG. 3

FIG. 4

Fig. 1 is a side elevational view of a cable cutter head, showing our new design.

Fig. 2 is a front elevational view of the cable cutter head as shown in Fig. 1.

Fig. 3 is an end elevational view of the cable cutter head taken from the left end as shown in Fig. 2.

Fig. 4 is an end elevational view of the cable cutter head taken from the right end as shown in Fig. 2.

We claim:

The ornamental design for a cable cutter head, substantially as shown.
